UNITED STATES PATENT OFFICE

WILLIAM F. SCHENKE, OF MARINETTE, WISCONSIN

COMBINATION SCREEN AND STORM WINDOW

Application filed October 25, 1928. Serial No. 314,964.

This invention relates to combination storm and screen windows.

In the usual construction of storm and screen windows, it has been necessary to take out the complete storm window, store it, and replace it with a screen. This has necessitated considerable work as these windows are relatively heavy, large, and difficult to handle.

10 This invention is designed to provide a master frame which goes in the window and which interchangeably receives either storm window panels or screen window panels, so that the master frame may be left in place 15 all the time and the panels interchanged as required from the inside of the house and with the utmost ease.

Further objects are to provide a master frame which is so constructed that it may be 20 rabbeted and mortised on an ordinary wood working machine of the standard type, so that the master frame may be made with the utmost cheapness and facility.

A further object of this invention is to 25 provide a novel form of drain for the lower portion of the master frame, which is so constructed that it is permanently screened and may be opened or closed without altering the position of the screen, so as to permit 30 the free egress of water that may collect back of the master frame and yet prevent the entrance of flies.

An embodiment of the invention is shown in the accompanying drawings in which: 35 Figure 1 is an inside face view of the device;

Figure 2 is a sectional view on the line 2—2 of Figure 1 showing the lower panel opened out;

40 Figure 3 is a detail partly broken away of one of the corner portions of the master frame;

Figure 4 is a sectional view on the line 4—4 of Figure 3;

45 Figure 5 is a sectional view on the line 5—5 of Figure 3;

Figure 6 is a detail partly broken away showing the screen-closed drain shutter;

50 Figure 7 is a view from the rear side of

the shutter, such shutter being removed from the master frame.

Referring to the drawings, it will be seen that the device comprises a master frame having side portions 1, a top 2, and a bottom 3. This master frame is designed to be positioned permanently in the window casing by nailing it, fastening it with screws, or other fastening means, as desired. 55

It is adapted to interchangeably receive either storm window or glass panels or screen panels. The drawings show the device as equipped with the storm window panels.

The master frame has its top, bottom, and side portions all formed on the same machine and provided with a rabbeted or shouldered portion 4 (see Figures 3 and 5). This rabbeted portion extends all the way around the inner edge of the master frame. 70 It is to be noted that the shoulder comes approximately two-thirds of the distance inwardly from the edge of the master frame and leaves room for the formation of a mortise groove or channel 5 to receive the tenon 6 of the top or bottom portion of the frame, as each of the corner portions are made in the same manner. 75

It is thus possible to use standard material forming the master frame by merely 80 rabbeting it out approximately two-thirds of the distance without in any way interfering with the formation of a standard tenon for joining the corner portions. In actual practice, this has been found to be a 85 material of vital feature as it greatly reduces the expense of making the master frame and permits the use of ordinary types of stock and ordinary types of machines in its production. 90

The bottom portion 3 of the master frame is cut out, as indicated at 7 in Figure 1, and this cut-out portion is closed permanently by means of a screen 8. The screen is carried by a stationary metal sheet 9 secured to the bottom portion 3 and provided with a cut-out 10, corresponding to the cut-out 7 in the bottom portion of the master frame. The bottom edge of this screen is a selvage edge, 95 as indicated at 8' in Figures 6 and 7. The 100

metal member and the screen carried thereby are located on the inner side of the master frame.

The screen or wire mesh is held in place by upturned bottom lips 11 formed integrally with the member 9 and by a down-turned rear flap 9', as shown in Figure 7. This down-turned rear flap holds the upper edge and the main bottom of the wire mesh member or screen in place, and the upturned lips 11 securely retain the side bottom corners of the screen.

Further, the member 9 is provided with an inwardly turned vertical lip 12 for the reception of the free end of the pivoted shutter 13. This shutter is pivotally held in place by a wood screw 14 passing therethrough and through the member 9. The other end of the member 9 is provided with a screw 15. The upper edge of the pivoted shutter is folded over, as indicated at 16, to provide a finished portion, so that there is no chance of cutting the fingers of the user. Further, it gives a lip whereby the shutter may be manipulated, and forms a stop adapted to engage the upper end of lip 12 to limit the downward movement of shutter 13.

In the winter, when the storm sashes or panels are employed, the shutter is closed, but in the summer it may be rocked completely over to uncover the screen 8.

The upper or top portion 10 of the master frame is provided with a pair of downwardly extending cleats 17 which project inwardly and overhang the upper edge of the removable upper panel 18. The master frame is further provided with socket members 19 which cooperate with bolt fittings 20 carried by the lower portion of the upper panel, as shown in Figures 1 and 2, so that when the upper panel is in position, the bolts are passed into their socket members and thus retain the upper panel against downward motion.

The upper end of the upper panel is also held against outward motion by the clip 17. The upper panel is further provided with supporting hook-like members 21 which are apertured and receive the tongues of the fittings or clips 22 carried by the upper portion of the lower panel, as shown in Figures 1 and 2. The master frame is provided on its inner face with a locking and spacing rod 23 provided with notches cooperating with a clip 24 secured to the lower panel so that the lower panel 25 may be opened in, as shown in Figure 2, when desired. It is locked in place by rocking the member 23 upwardly and latching it behind the clip 26 carried by the master frame.

It is to be noted particularly that the lower sash or panel member 25 is provided with a projecting portion or lip 27 which is formed by rabbeting the entire sides, top,

and bottom of the lower panel. This lip 27 fits within the cut-out portion 4 of the master frame and into a cut-out portion or rabbeted portion 28 on the lower or bottom part of the upper panel 18. The upper panel is similarly provided with a lip 29 which extends up its side, and across its top and fits within the portion 4 of the master frame. Thus, the panels are held against motion in one direction by means of the master frame and are held against motion in the other direction by means of the clips and latches described above.

It is intended that the panels be interchangeable so that both storm panels and screen panels may be used, as required, without disturbing the master frame.

In positioning the panels, the upper panel is first slipped upwardly so that its upper edge passes beneath the clips 17 (see Figures 1 and 2). Thereafter, the catches or bolts 20 are operated to hold the upper panel against downward motion. Subsequently, the lower panel is hooked onto the upper panel by engaging the members 21 and 22. The lower panel is then rocked into place and fastened by the member 23 or by any other suitable type of fastener.

It is thus a very simple and easy matter to interchange or position the panels, as required. This positioning of the panel may be done by any one, from the inside of the house, with the utmost ease.

Further, although a master frame is employed and is fixed in position, nevertheless freedom for opening the lower panel is obtained by this invention.

In addition to the points enumerated above, it is apparent that the device presents substantially the same appearance as an ordinary storm window or screen, and that it is neat, serviceable, and easy to produce.

Although the invention has been described in considerable detail, such description is intended as illustrative rather than limiting as the invention may be variously embodied and as the scope of such invention is to be determined as claimed.

I claim:

A device of the class described including a frame having a cutout portion at its lower end, a screen member arranged over and normally closing the cutout portion, a metal sheet secured to the frame over the screen member and formed with a cutout corresponding to the cutout in the frame, said sheet having upturned bottom lips at the ends thereof for embracing one edge of the screen and a longitudinally disposed downturned flap at the other edge of the metal plate, a shutter pivotally connected to the metal sheet at one end and adapted to be normally positioned longitudinally of the cutout portion, a folded portion at the upper edge of the shutter member and an inturned lip at

one end of the metal sheet providing a guide for the pivoted shutter and adapted to be engaged at one end with the folded edge of the shutter to limit the downward movement of said shutter.

In testimony that I claim the foregoing I have hereunto set my hand at Marinette, in the county of Marinette and State of Wisconsin.
